(57) **CLAIM**

The ornamental design for a toothbrush holder, as shown and described.

DESCRIPTION

FIG. 1 is a perspective view of a toothbrush holder showing our new design;

FIG. 2 is a top plan view thereof;

FIG. 3 is a right side elevational view thereof;

FIG. 4 is a left side elevational view thereof;

FIG. 5 is a front end elevational view thereof;

FIG. 6 is a rear end elevational view thereof;

FIG. 7 is a bottom view thereof; and,

FIG. 8 is a top plan view thereof with the broken-line showing of a toothbrush being for illustrative purposes only and forming no part of the claimed design.

1 Claim, 6 Drawing Sheets
